FINISHING MACHINE

Albert William Hallam, Kettering, England, assignor to United Shoe Machinery Corporation, Paterson, N. J., a corporation of New Jersey

Application July 18, 1930, Serial No. 468,891, and in Great Britain September 10, 1929

7 Claims. (Cl. 12—78)

This invention relates to finishing machines and is herein illustrated as embodied in a device for burnishing sole edges of shoes.

Finishing machines of one class commonly comprise a scouring tool, better known as a Naumkeag pad, the work-engaging face of which is arranged to be rotated about a substantially vertical axis. In machines of this type as well as in others, it is advantageous in certain instances to be able to substitute one form of tool-head for another so that the machine may be adapted for performing a plurality of operations, in the repairing of shoes, for example, merely by the interchanging of different, relatively small and inexpensive tool mechanisms. Among other objects, the present invention is designed to provide a burnishing device which may be substituted for the Naumkeag pad attachment in a finishing machine of the type above referred to, without entailing any other changes in the machine, in order that it may readily be adapted for burnishing the sole edges of shoes merely by the substitution of the burnishing device for the scouring device.

To this end, the invention as herein illustrated consists in providing an oscillating tool carrier, a tool holder mounted to rotate on the carrier to allow any one of a plurality of tools on the holder to be brought into operative position and means for oscillating the carrier arranged to rotate about an axis parallel to the plane of oscillation of the axis of the holder and extending in a direction between the directions of the axis of the holder in its extreme positions. As herein illustrated, the above-mentioned relation is effected by so mounting the carrier that, as it is oscillated, the axis about which the holder rotates on the carrier moves into and out of alignment with the axis of the means for oscillating the carrier. By the use of such a construction the operating tools may be so mounted as to facilitate presentation of the work thereto and yet allow the means for oscillating the tool carrier to be so disposed as to enable a burnishing device constructed as above defined to be substituted for a scouring mechanism of the type above referred to without requiring any other changes in the machine.

To insure that an efficient driving connection shall be maintained between the carrier and the drive shaft when disposed as above described, a universal coupling is provided between the shaft and the carrier for maintaining the driving connection therebetween notwithstanding changes in their angular relation owing to the oscillation of the carrier. In accordance with another feature of the invention and as herein illustrated, the coupling, a self-aligning device, comprises ball-bearing elements associated with an eccentric portion of the drive shaft and the

carrier, the bearing elements being relatively rotatable in any direction.

Preferably, and as herein illustrated, the bearing element associated with the drive shaft is fixed thereto, but the other is slidably mounted in the carrier, so that only those components of the motion of the eccentric portion of the drive shaft extending transversely of the axis about which the carrier rotates are utilized to oscillate it.

These and other features of the invention will now be more particularly described by reference to the accompanying drawing and pointed out in the appended claims.

In the drawing,

Fig. 1 is a side elevation of a machine in which the invention is embodied,

Fig. 2 is a front sectional elevation taken along the line II—II of Fig. 1 but with the operating parts in a different position, and

Fig. 3 is a sectional plan view taken along the line III—III in Fig. 2.

The illustrated edge setting device is supported on a machine base (not shown) adapted also for the reception of a Naumkeag pad attachment, by means of a bracket 10 which rotatably supports a driving shaft 12 carrying loose and tight pulleys 14 and 16, respectively, in such a position that the same belt can be used for both the Naumkeag pad attachment and the edge setting device without being altered. When installed on a finishing machine of the type above referred to, the face 18 of the bracket 10 is seated against a boss on the machine frame and is held in assembled relation by bolts (not shown) which pass through holes 20 in the base of the bracket. The driving belt (not shown) may be transferred from either of the pulleys 14 or 16 to the other by means of a shifter 22 pivoted to the bracket 10 and having a control handle 24.

A stud 26 fixedly mounted on the bracket 10 substantially perpendicular to the drive shaft 12 provides a support for a carrier 28 which is oscillated on the support 26, by means later to be described, in order to cause tools 30 and 32 releasably mounted in a tool holder 33 to be oscillated to and fro rapidly.

The carrier 28 is oscillated when the shaft 12 is rotated by means of an eccentric crank 34 on the lower end of the drive shaft 12. It will now be apparent from Fig. 2 that, owing to the relation of the drive shaft 12 and the stud 26 about which the carrier 28 oscillates, it becomes necessary to provide a universal connection between the crank 34 and the carrier 28 in order continuously to maintain a driving connection therebetween. As illustrated, this connection comprises a ball bearing which serves effectively at the same time as both an antifriction and a

self-aligning connection between the crank 34 and the carrier 28. The inner race 36 of the ball bearing is held fixed on the crank 34 by means of a nut 38 while the outer race 40 of the ball bearing is received in a circular recess 42 in a block 44 the opposite outer faces of which are plane and parallel. The block 44 is also arranged to slide between the upwardly extending arms 46 of the carrier 28 in a direction parallel to that of the axis of the stud 26. The ball-engaging faces of the races 36 and 40 of the ball bearing are so shaped as to allow the outer race 40 to be rotated in any direction with respect to the inner race, in consequence of which a driving connection is maintained between the crank 34 and the carrier 28 notwithstanding changes in the angular relation of the carrier and the drive shaft 12; and, owing to the sliding connection between the block 44 and the arms 46 of the carrier 28, only those components of the crank's motion extending in a direction transverse to the axis of the stud 26 are utilized to oscillate the carrier 28. A guard 48 is secured to the bracket 10 in proximity to and surrounding the arms 46 of the carrier in order to prevent accidental contact of the operator or a piece of work with the carrier and to prevent oil from flying from it.

To allow the positions of the tools 30 and 32 to be interchanged when desired so that either of the tools may be brought into operative position, the tool holder 33 is mounted for rotation about a stud 50 integral with the carrier 28 and which, as herein illustrated, is substantially perpendicular to the axis of oscillation of the carrier. As a result of this construction it is apparent that the axis of the drive shaft and that about which the tool holder rotates with respect to the carrier are coincident when the carrier is in its intermediate position. The holder 33 is held locked with respect to the carrier 28 in either of two positions by means of lugs 52 extending from the upper surface of the holder 33 and adapted to be received within complementary recesses 54 in the carrier 28. The holder is thus held releasably in locking engagement with the carrier by means of a spring 56 retained in a recess between the stud 50 and a recess in the holder 33, the spring being retained in the position illustrated by means of a ring 58 which is held seated on a shoulder on the stud 50 by means of a screw 60. In order to interchange the positions of the tools 30 and 32 it is necessary merely to move the holder 33 downwardly against the stress of the spring 56 far enough to remove the lugs 52 from the recesses 54 and then to rotate the holder 33 through that angle by which the tools 30 and 32 are separated.

60 A finger hook 62 beneath the tools provides a convenient aid to the operator in presenting the work to the tool in operative position, and gas burners 64 are provided one at each side of the machine for keeping the tools at the desired temperature.

Having thus described my invention, what I claim as new and desire to secure by Letters Patent of the United States is:

70 1. In a burnishing machine, a tool carrier, means for oscillating said carrier comprising a drive shaft having an eccentric portion, and

means constructed and arranged to maintain a driving connection between said carrier and the eccentric portion of said shaft comprising bearing elements associated with said eccentric portion of the shaft and said carrier, said elements being relatively rotatable in any direction. 80

2. In a burnishing machine, an oscillating tool carrier, a rotatably mounted drive shaft having an eccentric portion for causing the carrier to be oscillated when the shaft is rotated, and a ball bearing for maintaining a driving connection between said carrier and the eccentric portion of said shaft, one race of the bearing being fixed to the eccentric portion of said shaft and the other race of the bearing being slidably mounted in said carrier, said races being relatively rotatable in any direction. 85

3. In a burnishing machine, in combination, an oscillating tool carrier, a tool holder mounted to rotate on said carrier to allow any one of a plurality of tools on the holder to be brought into operative position, and means for oscillating said carrier arranged to rotate about an axis parallel to the plane of oscillation of the axis of the holder and extending in a direction between the directions of the holder's axis in its extreme positions. 90

4. In a burnishing machine, in combination, an oscillating tool carrier, a tool holder mounted to rotate on said carrier to allow any one of a plurality of tools on the holder to be brought into operative position, and means for oscillating said carrier, said carrier being mounted so that as it is oscillated the axis about which the holder rotates moves into and out of alignment with the axis of said means for oscillating the carrier. 105

5. In a burnishing machine, in combination, an oscillating tool carrier, a tool holder mounted to rotate on said carrier about an axis perpendicular to the axis of oscillation of the carrier 115 to allow any of a plurality of tools on the holder to be brought into operative position, a drive shaft having an eccentric portion for oscillating said carrier, and connections between said shaft and said carrier comprising a ball bearing one 120 race of which is fixed to the eccentric portion of the shaft and the other of which is slidably mounted in said carrier.

6. In a burnishing machine, in combination, an oscillating tool carrier, means for oscillating 125 said carrier comprising a drive shaft having an eccentric portion, and means for maintaining a driving connection between the eccentric portion of said shaft and said carrier comprising a bearing member mounted to slide in said carrier 130 and a bearing element connected with said first-mentioned bearing member fixed to the eccentric portion of said shaft, said bearing element and member being constructed and arranged to allow relative rotation therebetween in any direction. 135

7. In a burnishing machine, an oscillating tool carrier, a drive shaft having a crank, means for maintaining a driving connection between said carrier and said crank to cause it to oscillate the carrier when the shaft is rotated, comprising a 140 block arranged to slide in the carrier and a bearing connecting said block and the crank on said shaft constructed and arranged to allow relative angular displacement of the block and crank. 145

ALBERT WILLIAM HALLAM.

CERTIFICATE OF CORRECTION.

Patent No. 1,937,819.

December 5, 1933.

ALBERT WILLIAM HALLAM.

It is hereby certified that error appears in the printed specification of the above numbered patent requiring correction as follows: Page 1, line 59, for "ball-bearing" read bearing; and that the said Letters Patent should be read with this correction therein that the same may conform to the record of the case in the Patent Office.

Signed and sealed this 20th day of February, A. D. 1934.

E. M. Hopkins
